ROTARY COMPRESSOR OR VACUUM PUMP

Arthur John Northey, Parkstone, England, assignor to Northey Rotary Engines Limited, Townsville, Australia

Application July 24, 1934, Serial No. 736,797
In Great Britain August 25, 1933

3 Claims. (Cl. 230—141)

This invention relates to rotary air or gas compressors, vacuum or liquid pumps or similar devices, more particularly of the kind comprising a pair of cylindrical chambers which intersect or 5 penetrate one into the other and each fitted with a rotor comprising a cylindrical body portion of less diameter than the cylinder and a projecting arm or piston, extending towards the cylinder walls. These rotors are mounted upon 10 parallel shafts one in each of the cylinder spaces, and each rotor body is suitably cut away so as to allow the associated projecting arms or pistons to pass one another in the course of their revolution. The shafts carrying the rotors may 15 be suitably geared together or otherwise arranged so that they rotate in relatively opposite directions and may be driven by any suitable motor either electric, internal combustion or other form.

20 One object of the invention is to obtain efficient compression or evacuation of charges of air or other gaseous fluid.

Another object of the invention is to provide an improved form of liquid pump.

25 A further object of the invention is to provide an improved form of motor driven by compressed air or by water power.

The invention consists in a compressor, vacuum pump or liquid pump, or similar device 30 in which a pair of coaxial bladed rotors, rotating in opposite directions within a chamber, and drawing in a charge of air or other gaseous fluid, or liquid between the trailing sides of the blades simultaneously with the compression 35 on the leading sides of said blades of the charge previously drawn in, is designed so that any compressed charge remaining in the chamber when the delivery valve closes, does not become a loss as in a reciprocating compressor, but expands into the suction charge already drawn in thereby raising the pressure thereof, practically the whole of the remainder of the compressed 40 charge being on the leading or compression side of the rotor tips on the next stroke of the rotors.

45 The invention also consists in the further features hereinafter described and claimed.

Referring now to the accompanying drawings: Figure 1 is a cross-sectional view of a 50 compressor constructed according to the invention and

Figure 2 a longitudinal sectional elevation thereof;

Figure 3 a view similar to that shown in Figure 1 of a modified form of compressor, and

55 Figure 4 a longitudinal sectional plan thereof;

Figure 5 one arrangement for bypassing the charge from the compression side of the rotors to the induction side thereof.

In carrying the invention into effect according to the embodiment illustrated in Figures 1 and 2, the compressor or evacuator comprises a main water cooled chamber *a* which is formed by two intersecting cylindrical bores. Within these bores two rotors *b* and *b'* revolve simultaneously in opposite directions, being carried on two parallel shafts *c* and *c'* which are concentric with the bores.

The rotors *b* and *b'* are each formed with a blade *d* which projects outwards towards the inner wall of each of the bores of the chamber *a* and are provided with recesses or pockets *e* on their peripheries to enable the blades *d* to perform a complete revolution. The rotor shafts *c* and *c'* are each provided at one end with a gear wheel *f*, the two gear wheels being of the same size and meshing one with the other so that the rotors are maintained in correct angular relationship one to the other and no variation in relative angular velocity can take place between them. The rotors may be driven by any suitable motor, either electric, internal combustion or other form, connected to the driving member *g* mounted upon one of the rotor shafts *c* and *c'*.

In the upper and lower walls of the chamber *a*, near the point of intersection of the two bores constituting the said chamber, are provided inlet and exhaust ports *h* and *i* which are controlled by non-return valves *j* and *k* respectively, the valve *j* controlling the air or other gaseous fluid passing through the inlet *h* from the conduit *l* whilst the valve *k* controls the air expelled through the conduit *m*.

The control valves *j* and *k* preferably comprise a fixed disc *n* having its seating in the compressor or evacuator casing and provided with a series of orifices *o* arranged in annular formation and normally covered at one end by a ring *p* which is pressed against one of the faces of the disc *n* by means of a spring *q*, the other end of which engages within an annular groove provided in a fixed extension *r* of the said disc *n*.

The operation of the compressor or evacuator is as follows:—

The rotors *b* and *b'* revolve in the direction indicated by the arrows in Figure 1, and as they move from the position shown in this figure which is the commencement of the suction stroke, the volume enclosed between the trailing sides of the blades *d* increases and air or other gaseous fluid

is drawn through the inlet valve *j*. At the same time, the volume enclosed between the leading sides of the blades is reduced, so that as the rotors revolve, the previous charge of air or other gaseous fluid contained between the leading sides of the blades is subjected to compression, and when this compression reaches a predetermined value—usually governed by the amount of loading on the non-return discharge valve *k*, the air or other gaseous fluid under pressure will be discharged through the conduit *m* into a tank or reservoir *z* (Figure 5) or wherever it is required.

The end of the compression stroke is reached when the blades on the rotors reach a position 15 immediately above the delivery valve *k*. The position of the rotors at this stage is approximately that shown in Figure 1 except that they are inverted. By the time the rotors reach this position, most of the compressed air or other gaseous fluid will have been expelled through the delivery valve *k*.

As the rotors move on from the position representing the end of the compression stroke, the two blades move upwards, lying between the two 25 rotor shafts. Both valves *j* and *k* automatically close and any small volume of compressed air or other gaseous fluid which may be contained in the space *s* is released and expands through the whole chamber *a*, raising the pressure therein to 30 a value above that of atmosphere, that is to say, the chamber is supercharged. When the rotors again reach the position shown in Figure 1, practically the whole of the supercharged air or other gaseous fluid will be contained in the space 35 on the leading side of the rotors, that is in the volume which is being compressed. The only part of the charge which must fall to atmospheric pressure before further air can be drawn in, is that then contained in the space *s* and as this is 40 a very small percentage of the total volume of air or other gaseous fluid its effect on the efficiency is negligible. The supercharging effect will naturally be greater the higher the delivery pressure of the compressor.

45 In the modified form of compressor illustrated in Figures 3 and 4 the non-return valves *j* and *k* are dispensed with, the inlet and outlet ports *t* and *u* being directly controlled by the rotors *b* and *b'*. The said ports *t* and *u* may be arranged 50 in pairs in the side walls of the chamber *a*, one on either side of each of the rotors, the inlet ports *t* being in alignment as are also the outlet ports *u*. The inlet ports *t*, communicate by means of the passages *v* in the compressor casing, 55 with the air or other gaseous fluid inlet conduit *w* whilst the outlet ports *u* are in communication with the air or other gaseous fluid outlet conduit *x* by means of the passages *y*.

The ports *t* and *u* are of curved segmental 60 shape and adapted to be opened and closed by the rotors which are of the same shape as those already described with reference to Figures 1 and 2.

It will be seen from Figure 3 that the compressor 65 operates in a similar manner to that shown in Figures 1 and 2, the blades *d* moving in the direction of the arrows to commence the induction stroke. As the blades move apart the inlet port *t* is uncovered by its rotor *b* so that 70 air or other gaseous fluid is drawn through the conduit *w* and passages *v* into the space *s* between the blades. Further movement of the rotors causes the outlet port *u* to be uncovered by the rotor *b'* air or other gaseous fluid under pressure 75 being discharged therethrough into the passages

y and discharge conduit *x*. The rotors now reach a position approximately similar to that shown in Figure 3 except that they are inverted. Both the inlet and the outlet ports *t* and *w* are now closed by their respective rotors and any small 5 pocket of compressed air remaining is trapped in the space *s* between the blades as in the arrangement shown in Figures 1 and 2. This pocket of compressed air or other gaseous fluid is expanded 10 into the chamber *a* in a similar manner to that already described, as the blades move upwards, thereby raising the pressure to a value above that 15 of the atmosphere.

It will be clear from the above description that the induction and compression stages are produced in a common chamber by means of a continuous and uniform rotary motion, so that no 20 inertia forces have to be considered. The compressor may be perfectly balanced, and as the bearings and gears are the only wearing parts, 25 speed of revolution is not limited by mechanical considerations. The radial and axial clearances by the rotors are very small, so that the leakage losses are low and the volumetric efficiency is maintained in service, while for the same reason 30 as no internal lubrication is absolutely necessary, the air or other gaseous fluid may be compressed and delivered free from any lubricating oil vapour. In some applications this point is of importance, but probably the main advantage of 35 the design is that it combines the positive delivery at relatively high pressures of a reciprocating compressor with high speeds of revolution, so that output in relation to weight and cost is very favourable.

A compressor as above described when used for road compressor work or any work where the amount of air used is varying, can be controlled or governed by by-passing the air from the compression side of the rotors to the induction side 40 thereof.

One such arrangement is shown diagrammatically in Figure 5, according to which a by-pass conduit *l* extends from the compression side of the rotors to the suction side thereof, and has 45 mounted therein a spring loaded valve *2*. The said valve normally cuts off communication between the discharge conduit *m* and the suction side of the compressor, the compressed charge being discharged into the tank or reservoir *z* 50 through the conduit *3* which latter is provided with a non-return valve *4*. As soon as the pressure within the tank or reservoir *z* reaches a predetermined pressure the valve *2* is raised from its seat by any suitable means such as a pressure 55 operated piston or electric device controlled by the pressure in the tank *z*, thereby allowing any further charges to pass up through the by-pass *l* to the suction side of the compressor.

By automatically controlling the time of opening of the by-pass valve by spring means or other governor, the pressure in the container can be kept at any desired mark whether the amount of air used be little or up to the maximum output 60 of the compressor.

The device constituting the invention may also be used for pumping liquids and may be particularly adapted for use as a suction or vacuum pump.

It can also be used as a motor driven by compressed air as, for example, in the operation of 70 pneumatic tools or may be driven by water.

I claim:—

1. A compressor or vacuum pump comprising 75 the combination of a pair of cylindrical chambers

which intersect or penetrate one into the other, a pair of co-acting contacting cylindrical rotors, rotatable in opposite directions within said chambers, means for admitting air to said chambers and cutting it off, and means for delivering air therefrom and cutting off said delivery, a blade on each said rotors, extending outwardly toward the casing and a recess in each said rotors, adjacent its blade, the blade on the recess side and the recess on the blade side forming a continuous concave curve, the construction and arrangement being such that the air is compressed between the leading radial surfaces of the two blades, and the recess and blades serve to transfer the compressed gas remaining in the recess after the closing of the delivery means, to the suction side of the compressor.

2. A compressor as claimed in claim 1 in which the means for admitting air to said chambers and cutting it off, and the means for delivering air therefrom and cutting off said delivery, comprises inlet and delivery ports arranged in each side of the chambers adjacent to the sides of the rotors so as to be covered and uncovered by the bodies of said rotors as they rotate. 5

3. A compressor as claimed in claim 1 in which the means for admitting air to said chambers and cutting it off, and the means for delivering air therefrom and cutting off said delivery, comprises inlet and delivery ports arranged in the rotor casing and which are opened and closed by means of non-return valves. 10 15

ARTHUR JOHN NORTHEY.
